Primary Examiner — Calvin E Vansant*Assistant Examiner* — Mark T. Philipp(74) *Attorney, Agent, or Firm* — Allen, Dyer, Doppele & Gilchrist, P.A.(57) **CLAIM**

The ornamental design for a pump enclosure, as shown and described.

DESCRIPTION

FIG. 1 is a front, top, right side perspective view of the design thereof:

FIG. 2 is a rear, bottom, left side perspective view of the design of FIG. 1;

FIG. 3 is a front view of the design of FIG. 1;

FIG. 4 is a rear view of the design of FIG. 1;

FIG. 5 is a top view of the design of FIG. 1;

FIG. 6 is a bottom view of the design of FIG. 1;

FIG. 7 is a right side view of the design of FIG. 1; and,

FIG. 8 is a left side view of the design of FIG. 1.

Broken lines illustrate subject matter outside the boundaries of the claimed invention, and form no part thereof.

1 Claim, 7 Drawing Sheets(56)
